(57) **CLAIM**

The ornamental designs for a ladder support, as shown and described.

DESCRIPTION

FIG. 1 is a top, front, right, perspective view of a ladder support, illustrating an embodiment of the design;

FIG. 2 is a front elevation view corresponding with FIG. 1; FIG. 3 is a rear elevation view corresponding with FIG. 1; FIG. 4 is a left side elevation view corresponding with FIG. 1;

FIG. 5 is a right side elevation view corresponding with FIG. 1;

FIG. 6 is a top plan view corresponding with FIG. 1; and, FIG. 7 is a bottom plan view corresponding with FIG. 1. The broken lines in the drawings are included for the purpose of illustrating portions of ladder support and form no part of the claimed design.
